ELECTRON EMITTER

Nicholas Anton, 1226 Flushing Ave., Brooklyn, N.Y.

Filed Dec. 28, 1954, Ser. No. 477,983

20 Claims. (Cl. 313—54)

The present invention relates to electron emitters and particularly to an emitter in which atomic energy is utilized to produce the electrons.

At the present time, cathodes for electron discharge tubes such as vacuum tubes and the like, are generally either thermionic or secondary-electron emitters and these cathodes are operated in closed vessels which are either under vacuum or are filled with special gases at predetermined pressures. In such closed vessels there is also provided a second electrode or anode which is operated at a positive potential and directs the action of the electrical field between the anode and the emitter. The emitted electrons are attracted to the plate, constituting a current flow, which may be controlled by one or more other electrodes in well known manner.

Thermionic emission is the emission of electrons from a metal which has been heated, generally to incandescence. In such emission an electron about to leave the metal induces a positive charge on the surface behind it, this action giving rise to a potential barrier which must be overcome before electrons can escape to become free electrons in space. The value of potential of the barrier is commonly given in terms of electron volts and is called the work function of the metal. In order for electrons to penetrate the potential barrier and escape from the metal surface they must possess a minimum energy equal to the work function. At room temperature the energy of electrons is much less than the work function, and consequently in conventional cathodes it is only by heating the metal that the electrons acquire sufficient additional energy to escape from the metal surface.

Secondary emitters depend upon electromagnetic radiation or high energy electrons for the release of free electrons. When radiation or high energy electrons are incident upon the surface of secondary-emitting material they impart their energy to the electrons in the material and if the imparted energy is greater than the work function, secondary electrons are emitted from the surface of the material.

As stated above, both thermionic and secondary emitters are in use at the present time. Both, however, have disadvantages. Thermionic emitters have the disadvantage that their life is limited due to the evaporation of the emissive coatings at high temperatures. Moreover, due to that evaporation, contamination of the other tube elements occurs during operation. Also, due to the high temperature conditions, the filaments used to heat the emitting coatings often burn out. Another disadvantage of such thermionic emitters is that there are limited conditions under which they may be operated, that is, either in a vacuum or in an atmosphere of gas which does not adversely affect the work function of the metal nor react chemically with the metal. In addition, there is a problem involved in supplying the energy for the emitter to keep it at high temperature, and in dissipating the heat developed in the thermionic emitter. In some ap-

2

plications, where it is desirable to provide a constant and sufficient rate of emission, it is necessary to provide special means for maintaining constant emitter temperature.

Secondary emitters have long life and no problem of heat dissipation is involved. Nevertheless, these emitters also have disadvantages, among which may be mentioned the dependence of the emission of secondary electrons on the quantity and intensity of the incident primary radiation or the primary electrons, and the fact that the yield of secondary electrons per incident electron is relatively small.

The atomic emitter of the present invention overcomes the disadvantages associated with thermionic and secondary emitters. This emitter possesses an indefinite life, has a constant rate of copious electron emission, can be operated at any desired temperature, either in a vacuum or in any gaseous atmosphere, and does not require an external source of power for heating or of incident radiation.

The atomic emitter of my invention comprises but two essential components: a radioactive material of long life which emits beta or alpha particles or both, and a semi-conductor (as used herein, the term "semi-conductor" means a material which under the band theory of solid-state physics has all of its inner bands filled and its conduction bands only partially filled above absolute zero temperature. It is a dielectric with a limited degree of ion mobility or positive charge movement therewithin, sometimes described in terms of the movement of "holes" within the material and which is substantially ionized under the influence of incident sub-atomic charged particles without permitting the free conduction of ions therein). The radioactive material is supported on a base serving as an electrode or may be self-supporting, and the semi-conductive material is in turn closely associated with the radioactive material, as by being deposited or laminated upon it. Beta or alpha particles emitted by the radioactive material pass through the semi-conductive material and in so doing expend their energy in ionizing the molecules of that material and releasing a number of free electrons. The thickness of the semi-conductive material is preferably chosen to have at least a minimum value such that the beta or alpha particles emitted by the radioactive material cannot emerge therefrom to produce high efficiency and low noise level.

An electric field is caused to act on the atomic emitter so that secondary electrons generated at or near the interface of the radioactive material and the semi-conductive material by action of the radioactive particles emitted by the radioactive material will be acted upon by the electric field and will be urged toward the outer surface of the semi-conductor. Since a thin layer of amorphous or crystalline dielectric or semi-conductor when polarized by the action of an electric field acts like a dense layer of heavy gas, these secondary electrons under the accelerating action of the field will further ionize molecules of the semi-conductor, thus generating additional free electrons. These additional free electrons are in turn accelerated by the field and the action is repeated resulting in an avalanche of electrons like a Townsend avalanche in a gas, and this avalanche ultimately breaks through the surface of the semi-conductor to become free electrons of relatively low energy which by proper design can be made just sufficient to provide a cloud source of electrons just outside the emitter, similar to the space charge of a thermionic emitter, but with the desirable properties mentioned above. The electron amplification thus produced is comparable to that obtained in Geiger counters and each electron liberated by the original ra-

dioactive ionizing event is capable of releasing 10^3 to 10^6 free electrons from the emitter under the action of the external electric field.

It is accordingly an object of the invention to provide an electron emitter requiring no source of power for heating and having uniform emission and long life.

It is a further object of the invention to provide an electron emitter having a radioactive material as an original energy source for initiating the production of electrons.

It is another object of the invention to provide in such an emitter a semi-conductive material from which electrons are freed as emission from the radioactive material penetrates into the semi-conductive material.

It is still a further object of the invention to subject such an emitter to the action of an electric or electromagnetic field of such intensity and polarity to cause the electrons produced by ionization induced by the radioactive material to move and to cause cascade ionization, the field also supplying the energy for drawing all or most of these electrons into space outside the emitter.

It is yet a further object of the invention to provide an emitter having a readily adjustable emission under the control of an applied field.

Other objects and features of the invention will be apparent when the following description is considered in connection with the annexed drawings, in which,

Figure 1 is a transverse cross-sectional view of one embodiment of my invention; and

Figure 2 is a side elevation of the device of Figure 1, portions of the outer elements being broken away in order to show the interior construction.

Referring now to the drawings, there is shown at 10 a supporting element for a layer of radioactive isotope 11. As shown in the drawings, the supporting element 10 is a metallic wire which, in a particular instance, was of platinum and had a diameter of eight one-thousandths (0.008) of an inch. The supporting element may, however, be any other metal or conductive layer on an insulating support and, in fact, may be omitted provided that the radioactive material be conductive and rendered self-supporting alone or in combination with the semiconductor, which may be done for example by forming the radioactive material in the form of a wire, ribbon or plate or in some cases by mixing powdered radioactive material with a powdered insulating or metallic binder and then forming it in a suitable rigid shape by powder metallurgy. When a metallic base is used, the metal chosen should preferably be one which is not subject to rapid oxidization or contamination which would offer a layer of high resistance to the passage of current. Platinum is desirable for the reason that it is highly stable and may have other materials readily coated thereon. Other metals, such as, for example, nickel, are also suitable.

Plated, deposited or otherwise applied on the base wire 10 is a layer of radioactive material 11, which material may, as has been indicated, be an emitter of either alpha or beta particles or both. A gamma emitter can be used but is not desirable since it requires some shielding in order to assure personnel safety. It will also cause some electrical noise by its action on other tube elements and envelope. In the device shown in the drawing, the layer 11 is preferably technetium 99 which is an emitter of beta particles, and this layer is approximately 0.0001 inch to 0.001 inch thick. The thickness or amount of radioactive material is not critical. The radioactive material should be thin enough to permit a very large majority of its emitted beta particles (or alpha particles or both) to emerge from it and to make possible a high efficiency of emission per unit area. Also, it should present low electrical resistance to current flow. Preferably an amount is applied which will produce sufficient initial ionization to obtain the desired

total emission at the operating conditions used. As has been indicated, other radioactive materials which emit charged sub-atomic particles may be utilized, the primary requirement being that the materials have a relatively long half life, values greater than one year being the most practical. Promethium 147, strontium 90, carbon 14 and thallium 204, in addition to the technetium also mentioned, satisfy this requirement.

Emitters of alpha particles having long half lives may also be utilized if some gamma emission can be tolerated. Examples of such emitters are radium, thorium of atomic weight of 230 or 232, and uranium of atomic weight 238 or 234. Polonium, a pure alpha emitter, may be used in specific cases. Of course, any chemical compound of any of the foregoing elements could also be used.

Deposited or otherwise applied on the layer 11 is a layer 12 of a semi-conductive material. In a particular instance this layer 12 was of magnesium oxide deposited at the rate of 4 milligrams per square centimeter of the surface of the technetium layer 11. This thickness was selected as large enough to absorb substantially all the beta electrons emitted by the radioactive material and to provide sufficient avalanche multiplication. For other radioactive materials having different maximum energy values of emitted beta electrons, corresponding thicknesses of semi-conductors would be used, in accordance with the considerations discussed below. Any semi-conductive material may be used, such as aluminum oxide, barium carbonate, silicon oxide, cadmium sulphide, selenium, germanium, cuprous oxide, zinc oxide, arsenic oxide, germanium oxide, or mixtures of the materials mentioned. In general, materials used for transistors may also be employed. Each of the aforementioned materials will exhibit different efficiencies, and even the same material will show different efficiencies depending upon the manner in which it is applied. Preferably, the material is applied so as to provide as large a surface area as possible, by maintaining high roughness of the outer surface. A preferred material is magnesium oxide, especially in a crystalline form obtained by depositing it by evaporation in a low pressure atmosphere of oxygen of the order of 5 mm. of mercury.

Surrounding the elements 10, 11 and 12 already mentioned, is a control grid 13 which is constructed in the manner customary in the usual electron tube and surrounding this may be a second similar grid 14. These grids 13 and 14 are shown merely as illustrative of any number of electrodes which may be used to control the produced free electrons in any desired manner. Surrounding all of the elements mentioned is a plate or anode 15 which is connected in the usual manner to the positive side of a direct voltage source, the negative side of which is connected to the technetium layer either through the conductive base material 10 or directly in cases where that base material is omitted. It will be understood that the emitter may be at a negative potential with an accelerating screen or grid electrode at ground potential, followed by control and collecting electrodes, and still other arrangements may be used, the only important criterion being that electrons must be subjected to an accelerating field to pass outwardly through the semiconductor and away from the radioactive material.

The operation of the device has been generally described. However, the detailed operation of the embodiment of the invention illustrated in the drawings will now be discussed, assuming that a source of direct potential has been connected between the collecting electrode or anode 15 and the platinum wire 10 in the usual manner.

Beta particles are emitted by the radioactive layer 11, these particles proceeding randomly in all directions. Since the base wire 10 is relatively thin, the particles emitted in the direction of base wire 10 will pass through the wire 10 to the opposite side thereof into the radioactive layer 11 and semi-conductor 12 on that side. Thus

all of the beta particles emitted by the radioactive layer 11 must necessarily pass into the layer 12. As is well known, the beta electrons emitted by technetium have a complete spectrum of energy levels, extending up to 0.3 million electron volts (m.e.v.). These electrons are of too high energy to be directly useful in an electron tube, but by the present invention are converted into useful low energy electrons in far greater numbers. As the beta particles enter the semi-conductor layer 12 they expend their energy in ionizing the molecules thereof and releasing low energy secondary electrons. The number of secondary electrons liberated in the semi-conductor layer 12 for each beta electron is equivalent to the energy of the ionizing beta particle divided by the ionization voltage, and is of the order of from 5 to 6 thousand times the number of high energy beta particles.

The electric field resulting from the potential difference between the anode 15 and the wire 10 will cause these secondary electrons to be accelerated within the semi-conductor, within which they have a degree of mobility. Secondary electrons generated at the interface of the magnesium oxide layer 12 and the technetium layer 11 will ionize further molecules of the magnesium oxide as they proceed from the interface toward the surface of the layer 12 under the influence of the applied electric field and will thus generate additional secondary electrons. These additional electrons are in turn accelerated and this action is continuously repeated resulting in a Townsend avalanche, the semi-conductor acting like a dense gas in this respect. This avalanche proceeds outwardly until the electrons burst out from the semi-conductor and become free electrons, of useful low energy, which flow to the anode just as in conventional electron tubes, and may be employed in the same manner as in conventional tubes.

The electrons leaving the semi-conductor leave it positively charged at its surface, which increases the electric potential at the outer surface of the semi-conductor and correspondingly increases the electric field gradient acting within the semi-conductor to generate the avalanche. This condition arises because of the high resistivity of the semi-conductor layer 12 which prevents the positive charge from decaying immediately. Thus a relatively intense electric field is produced within the magnesium oxide layer, the field intensity being greatest at the surface and least at the interface and therefore in such a direction as to enhance the yield of secondary electrons by increasing the acceleration of each secondary electron and thereby increasing the avalanche effect. In this way the number of emitted free electrons is increased until an equilibrium is established.

It will be seen that if the potential at the semi-conductor outer surface were to equal or exceed the anode potential, no electrons would flow to the anode (except for a few of original high kinetic energy). This would soon result in dissipation of the positive surface charge, and dropping the surface potential to an equilibrium value just sufficient to permit enough free electrons to flow to the anode to sustain the surface potential at that value. This value is estimated to be very slightly below the anode potential, by perhaps a few hundredths of a volt.

The various factors which determine the resultant emission are: (1) the strength of the radioactive source, (2) the nature and thickness of the semi-conductor and (3) the applied field.

The number of free electrons emitted is a function of the number of primary beta (or alpha) particles which is in turn dependent upon the strength of the radioactive material. For any given radioactive material the ratio of free electrons to beta (or alpha) particles is a constant at any given potential difference between the anode and base, and for a given size and material of semi-conductor, providing a very stable type of emitter. Additionally, the ratio increases exponentially as the potential difference between the anode 15 and the base 10 is increased, per-

mitting use of the anode potential to determine the electron current up to a saturation value. A limiting factor may also be arcing or breakdown in the semi-conductor, depending upon the dimensions and values used.

As indicated above, the semi-conductor converts the higher-energy radioactive product particles into low-energy copious free electrons. For extremely thin semi-conductors, the radioactive material particles will pass completely through without significant interaction with the semi-conductor, and the resultant free electrons are essentially only the beta particles with too high energy and too low number to be useful. As the thickness of the semi-conductor is increased, more and more beta particles interact with the semi-conductor and in the presence of the impressed electric field the avalanche or cascade action begins, and increasing number of free electrons are produced. Since it is desirable that the free electrons have low energy and that no beta particles themselves become free electrons, the semi-conductor is chosen to have a thickness which will absorb substantially all beta particles emitted from the radioactive source. Since for each radioactive source the beta particles have a continuous energy spectrum with a well defined inner energy limit, this can be readily done. In the case of technetium, a thickness of semi-conductor providing an area density of 4 milligrams per square centimeter is sufficient. As will be recognized readily this value applies for any of the semi-conductors. For other radioactive sources, their upper beta energy limits are well known, as are the area densities necessary for absorption of those energies, and such area densities will be used in determining the thickness of semi-conductor by the simple relationship that the thickness equals the area density (mg./cm.²) divided by the volume density (mg./cm.³).

It will be understood that for such thicknesses the lower energy beta particles will be absorbed in the initial portion of the semi-conductor. This is not important, since the major portion of the total energy of the beta particles resides in the higher energy ones.

As the thickness of the semi-conductor is increased beyond the minimum value required for beta absorption, a maximum free electron supply is reached, beyond which thickness the number of free electrons diminishes. This occurs for thicknesses greater than that for which the secondary electrons no longer have energies exceeding the work function of the material. It will be understood that incident beta particles have energies exceeding both the ionizing potential and the work function by many, many times. The first secondaries produced are given a substantial portion of the beta particle energy and are energetic enough to produce themselves a multiplicity of other secondaries with lesser energy but still energetic enough to produce still others. This process continues with gradual diminishing of the secondary electron energy despite the acceleration given by the electric field, because of the highly limited mobility of electrons in the semi-conductor. Ultimately, if the semi-conductor is too thick, the secondaries would have too little energy either to continue the avalanching process or to become free electrons, and beyond this point increased semi-conductor thickness only serves to reduce the free electron flow. The optimum thickness is generally somewhat greater than the minimum thickness determined by complete beta absorption. For less than this minimum thickness, the beta particles are being inefficiently utilized, and incomplete avalanching occurs, leading to considerably reduced free electron output.

As will be seen from Fig. 1, the base 10 serves as an electrode for the return circuit from plate 15. To facilitate current flow, the semi-conductor may be desirably chosen to have a contact potential higher than that of the radioactive material, and the radioactive material may have a contact material higher than that of the base.

In use, the emitter of the present invention may be used wherever conventional emitters are used and in

the same way. With grid electrodes 13 and 14 omitted, the device of Fig. 1 is a diode, conductive only when the plate on anode 15 is positive relative to the emitter base 10. In the diode case, it is not necessary to have a space between the plate and the semi-conductor; the plate may be formed on the semi-conductor surface, as by laminating, plating, depositing etc. This will provide a solid diode rectifier requiring no envelope, evacuation or gas filling.

For grid controlled operation of the device of Fig. 1, electrode 13 may be used as a control grid and electrode 14 as a screen grid. Further electrodes serving as control, screen, mixer or suppresser grids may be added.

In one preferred form, grid 13 serves as a field-applying electrode, in the same manner as plate 15 was described above. In such case grid 13 is placed close to semi-conductor 12 and is made to have a large mesh so as to capture but few electrons. It is made positive relative to the emitter electrode, and serves together with the emitter to provide a source of electrons in its vicinity. Grid 14 may then be the conventional control grid, and plate 15 serves as the anode for conventional grid-controlled operation. In this case grid 13 is preferably at or near ground potential, with electrode 10 negative with respect thereto, and the conventional cathode connections for the external circuit are made to grid 13. In effect, the cathode is formed by the emitter plus grid 13 in such case. Again, additional electrodes serving the usual functions in multi-grid tubes may be added.

Although in the drawings no envelope has been indicated, one would normally be supplied. It is not, however, necessary that the envelope be evacuated or filled with any special gas under any predetermined pressure conditions, since the action of electron generation is not affected by the atmosphere to which the emitter is subjected, contrary to the conventional thermionic and secondary emitters. However, where conventional forms of electron control are used it may be desirable to evacuate or control the pressure within the tube.

As has been indicated hereinabove the various elements of the device may be formed from a number of different materials, the combinations of materials utilized thus being large in number. Moreover, the exact physical arrangement may be considerably varied both in manners hereinabove suggested and in other ways. The base material may be omitted, connecting the layer of radioactive material directly to the negative terminal of the potential source when the radioactive layer is conductive and either deposited on an insulating support or is self-supporting. The shape of the support may be varied as desired; for example, it may be a wire as shown, or a ribbon, or a flat plate, or a plate which is curved, and may be covered with the radioactive material in part or throughout its area. In each instance it is only required that the semi-conductor be juxtaposed to the radioactive source, with a field impressed for urging electrons through and out of the semi-conductor to become free electrons. In particular, the cylindrical configuration shown in Fig. 1 is not essential; any configuration of radioactive material and semi-conductor may be used by which the beta or alpha particles or both are absorbed in the semi-conductor and permitting the field to be applied thereto.

By way of example, the radioactive material 11 may be inside the base 10, or on the side thereof opposite to the semi-conductor 12, so long as the base 10 does not appreciably absorb the beta particle energy. Where the radioactive material 11 is conductive, it may itself serve as the electrode and the base 10 may be dispensed with. Where the radioactive material 10 is not conductive, it may be powdered and mixed with metal powder and then formed into a solid by pressure, a binder or other powder metallurgy, to form the electrode.

While the semi-conductor has been described as suffi-

ciently thick to absorb all beta particles emitted by the radioactive material, this is not vital. This feature yields the advantage that the beta particles then do not become free electrons which could contribute markedly to the electrical noise level within the tube. Where such noise is not an important factor, other amounts of semi-conductor can be used and, in fact, the radioactive and semi-conductor materials could even be intimately intermixed to form a conductive element, as in a compressed powder mixture.

It will be understood that the theoretical explanation of the manner of operation of the present invention given in the foregoing specification is believed to represent a correct statement of the principles involved and the action taking place in the present invention. However, I do not wish to be limited in any way to or by the theory described, since other theories may also explain the action of the invention.

Since the combination of materials as well as the details of construction may be varied in the ways indicated above and in many other ways, I wish to be limited not by the foregoing description which was given solely for purposes of illustration, but only by the claims granted to me.

25 What is claimed is:

1. An electron emitter comprising a radioactive material and means for converting the energy of radioactive particles from said radioactive material into free electrons, comprising a semi-conductor in particle-receiving association with said first material.
2. An electron emitter comprising a radioactive material, an electrode in contact with said material, and a semi-conductor in contact with said radioactive material and separated from said electrode.
3. An electron emitter comprising an electrically conductive base, a layer of a beta particle emissive material in contact therewith, and a layer of a semi-conductive material in contact with said radioactive material.
4. An electron emitter comprising a conductive base, a layer of alpha particle emissive material in contact therewith and a layer of a semi-conductive material in contact with said radioactive material.
- 40 5. An electron emitter comprising a layer of semi-conductive material deposited on the surface of a radioactive material emitting particles other than gamma rays.
6. An electron emitter as claimed in claim 5, characterized in that said radioactive material is formed of at least one of the group of materials comprising technetium, carbon 14, strontium 90, thallium 204, promethium 147, polonium, radium, uranium 234, uranium 238, thorium 230 and thorium 232.
7. An electron emitter as claimed in claim 5, characterized in that said layer of semi-conductive material is formed of at least one of the group of materials including 55 aluminum oxide, magnesium oxide, silicon oxide, germanium oxide, arsenic oxide, barium carbonate, germanium, selenium, cuprous oxide and cadmium sulphide.
8. An electron emitter comprising a semi-conductor element, a radioactive source of sub-atomic charged particles adjacent thereto for injecting said particles into said element, and means for applying a unidirectional field within said semi-conductor to cause avalanching of secondary electrons therewithin.
9. An emitter as in claim 8 wherein said semi-conductor is formed of magnesium oxide and said source comprises technetium.
10. An electron discharge device comprising an anode and cathode, said cathode being formed of radioactive material and means for converting the energy of radioactive particles from said material into free electrons, comprising a semi-conductor in particle-receiving association with said first material.
11. An electron discharge device comprising a layer of semi-conductive material deposited on the surface of a radioactive material emitting particles other than gamma

rays, said radioactive and semi-conductive materials forming the tube cathode, and an anode spaced from said cathode.

12. An electron discharge device comprising an anode and a cathode, said cathode comprising a radioactive material and means for converting the energy of high energy particles from said material into free electrons, comprising a semi-conductive material in particle-receiving association with said first material.

13. Electrical apparatus comprising an electrode, an anode, a source of direct potential connected therebetween with the positive terminal connected to said anode, a radioactive material in contact with said electrode, a semi-conductive material in contact with said radioactive material and between said electrode and said anode whereby the electric field between said anode and said electrode multiplies the beta particles produced by said radioactive material by avalanching within said semi-conductive material.

14. Electrical apparatus comprising a support, a layer of radioactive material on said support, said material emitting particles other than gamma rays, a layer of semi-conductive material on said emitting layer, said layer of semi-conductive material being of a thickness to absorb substantially all said emitted particles, an anode spaced from said semi-conductive layer and a source of direct potential connected between said radioactive layer and said anode.

15. Electrical apparatus comprising an electrically conductive base, a layer of radioactive material emitting alpha and beta particles, said material having a half life of at least one year, and a layer of semi-conductive material deposited on said radioactive material, the thickness of said semi-conductive material being such that there are 4 grams of semi-conductive material per square centimeter of surface of said radioactive material, said thickness being sufficient to prevent penetration of said semi-conductive layer by said particles, said semi-conductive material being highly resistive to prevent rapid decay of positive charge induced in said semi-conductive material, an anode, a source of direct potential connected between said base and said anode to produce an electric field therebetween, said electric field causing a build-up of positive charge in said semi-conductive material thereby multiplying the electrons produced by said radioactive material by avalanching within the semi-conductive material.

16. An emitter as claimed in claim 5, wherein said semi-conductive material is magnesium oxide.

17. An electron emitter comprising an electrode, a radioactive material on said electrode and adapted to produce, high-energy particles, and means for converting said high-energy particles into a copious supply of low-energy free electrons, comprising a semi-conductor material in particle-receiving relation to said radioactive material and having the property of producing an avalanche of low-energy electrons in response to each of said high-energy particles impinging thereon.

18. An emitter as in claim 17 wherein said converting means further comprises means for applying an electric field to said semi-conductor material to produce said avalanche and draw said low-energy electrons from said semi-conductor material.

19. An electron discharge device suitable for both evacuated or gas atmosphere use, comprising an emitter formed by a source of radioactive particles and means absorptive of said particles for producing a multiplicity of free electrons, said means comprising a semi-conductor material in particle-receiving relation to said source, an electrode spaced from said source and a source of potential coupled between said electrode and said source, said discharge device also including at least one further electrode beyond said first electrode.

20. An electron emitter comprising a radioactive material and means for converting the energy of radioactive particles from said material into free electrons, comprising a semi-conductive material in particle-receiving association with said first material.
